(57) **CLAIM**

The ornamental design for a display screen or portion thereof with animated icon, as shown and described.

DESCRIPTION

FIG. 1 is a front view of a display screen or portion thereof with animated icon showing a first image in a sequence showing our new design;

FIG. 2 is a second image thereof;

FIG. 3 is a third image thereof;

FIG. 4 is a fourth image thereof;

FIG. 5 is a fifth image thereof;

FIG. 6 is a front view of another embodiment of a display screen or portion thereof with animated icon showing a first image in a sequence showing our new design;

FIG. 7 is a second image thereof;

FIG. 8 is a third image thereof;

FIG. 9 is a fourth image thereof; and,

FIG. 10 is a fifth image thereof.

The appearance of the animated images sequentially transitions between the images shown in FIGS. 1-5 and 6-10. The process or period in which one image transitions to another forms no part of the claimed design.

The dot-dash line perimeter illustrates a display screen or portion thereof and forms no part of the claimed design. The evenly-spaced broken lines show portions of the animated icon that form no part of the claimed design.
